Primary Examiner — David G Muller*Assistant Examiner* — Nathan M Johnston(74) *Attorney, Agent, or Firm* — The H.T. Than Law Group(57) **CLAIM**

The ornamental design for the drug delivery implements with translucent housing, as shown and described.

DESCRIPTION

FIG. 1 is a perspective view of an ornamental design for an embodiment of a drug delivery implement with translucent housing according to the present invention;

FIG. 2 is a front view thereof;

FIG. 3 is a back side view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of FIG. 12 with a cap separated from the drug delivery implement.

The broken lines illustrate portions of the drug delivery implements with translucent housing and form no part of the claimed design.

1 Claim, 5 Drawing Sheets---
